US00D907899S

(12) **United States Design Patent** (10) Patent No.: **US D907,899 S**
(45) Date of Patent: **** Jan. 19, 2021**

(54) **TEXTILE TAG**

(71) Applicant: **Kerry Deco**, Glendale, CA (US)

(72) Inventor: **Kerry Deco**, Glendale, CA (US)

(**) Term: **15 Years**

(21) Appl. No.: **29/673,287**

(22) Filed: **Dec. 13, 2018**

Related U.S. Application Data

(63) Continuation of application No. 16/185,255, filed on Nov. 9, 2018, now Pat. No. 10,699,603.

(51) **LOC (13) Cl.** **02-02**

(52) **U.S. Cl.**

USPC **D2/853**; D8/395

(58) **Field of Classification Search**

USPC D2/853, 895; D19/86, 65; D8/395, 394,
D8/396

CPC A44B 6/00; A44B 21/00; G09F 3/02

See application file for complete search history.

(57) **CLAIM**

The ornamental design for a textile tag, as shown and described.

DESCRIPTION

FIG. 1 is a front perspective view of a textile tag;

FIG. 2 is a rear perspective view thereof;

FIG. 3 is a front view thereof;

FIG. 4 is a rear view thereof;

FIG. 5 is a side view thereof;

FIG. 6 is a cross-sectional side view thereof;

FIG. 7 is a bottom view thereof; and,

FIG. 8 is top view thereof.

The broken lines in the drawings illustrate shade lines and the shading forms no part of the claimed design.

1 Claim, 1 Drawing Sheet
